UNITED STATES PATENT OFFICE.

FREDERICK KNIGHT, OF VICTORIA, BRITISH COLUMBIA, CANADA, ASSIGNOR TO JOHN GILBERT COLVILLE, OF VICTORIA, CANADA.

DRAIN VALVE.

1,420,559.

Specification of Letters Patent. Patented June 20, 1922.

Application filed December 15, 1919. Serial No. 344,772.

To all whom it may concern:

Be it known that I, FREDERICK KNIGHT, a subject of the King of Great Britain, and resident of Victoria, in the Province of 5 British Columbia, Dominion of Canada, have invented certain new and useful Improvements in Drain Valves, of which the following is a specification.

This invention relates to improvements 10 in drain valves for use on steam pipes, pipe lines, steam cylinders, etc., wherein drainage of excess steam and condensed water is necessary, and the objects of the invention are to provide a drain valve which is automatically closed by steam pressure, and is 15 automatically opened when released from steam pressure.

Further objects are to minimize the number of working members, and to mount the 20 working elements in the valve, so that they will be bodily removable when disassembling the valve, thereby providing for ready inspection or repair of the working parts.

25 It further has for its objects to provide a drain valve which can be employed to simultaneously drain one or more pipes and cylinders, and to simplify the construction and render the drain valve inexpensive, and 30 durable, and easy and effective in operation, and to permit of the valve when disassembled being readily reseated in its cooperating part of the casing, so that a reliable valve will at all times be obtained.

35 With the above and other objects in view, the invention consists essentially of the improved construction, hereinafter described in detail in the following specification and accompanying drawings.

40 In the drawings:—

Figure 1 is a side elevation of the improved drain valve.

Figure 2 is a vertical section through the valve casing showing part of the valve in 45 section.

Figure 3 is a top plan of the improved drain valve.

Figure 4 is a plan view of the upper portion of the valve casing as seen when looking upwardly.

Figure 5 is a vertical section of the upper portion of the valve casing.

Figure 6 is a side elevation of the upper portion of the valve casing.

55 Figure 7 is a vertical section through the

lower portion of the valve casing and showing the valve seat.

Figure 8 is a plan view of the lower portion of the valve casing showing the valve seat.

Figure 9 is a plan view of the underside of the lower portion of the valve casing.

Figure 10 is a side elevation of the valve.

Figure 11 is a top plan of the valve.

Figure 12 is a plan of the underside of the valve.

Like characters of reference refer to like parts in the several figures.

Referring to the drawings, A represents the valve casing formed in two portions 10 and 11, the upper portion 10 having laterally extending conduits 12 arranged in alignment and threaded internally for the reception of drain pipes.

The upper portion 10 of the casing is provided with a cylindrical chamber 13 which is normally closed by the under portion 11 of the casing, the said chamber 13 communicating with the conduits 12 through L-shaped ports 14, part of which are formed 75 in the side wall 15 of the chamber 13, while the completion of the lower arms of the L-shaped ports is formed in the lower portion 11 of the casing.

The lateral wall of the chamber 13 is 85 threaded internally as shown at 16, and the lower portion 11 of the casing is formed with a threaded upper end 17 adapted to make threaded engagement with the threaded portion 16 of the wall 15, and to limit 90 the movement of the portion 11, relatively to the portion 10, an annular flange 18 is provided, which abuts the upper portion 10 of the casing.

The lower portion is formed with a hexagonal or like nut 19, which facilitates tightening it into threaded engagement with the upper portion 10, and a central conduit 20 is provided in the lower portion.

This central conduit 20 is provided with 100 an enlarged lower threaded end 21, which may be connected to a waste pipe, and an upper enlarged end 22, which houses a spring 23 coiled around the stem 24 of the valve 25. This spring engages at the lower 105 end with the shoulder 26, and on the upper end with the annular recess 27 formed in the conical wall of the valve 25.

The lower portion 11 of the casing is formed with a valve seat 28, with which the 110

conical wall of the valve 25 coacts, and a cylindrical projection 29 is provided on the upper wall of the valve 25 and formed with a saw draught to facilitate grinding the 5 valve into the valve seat.

It will be particularly noticed by reference to the drawings, that the diameter of the valve 25 makes a good sliding fit in the cylindrical chamber 13, but this chamber 10 is provided on its lateral walls with by-passes 30, and the upper wall of the chamber is formed with a threaded conduit 33 for connection with a steam pipe leading to the valve chamber of a cylinder.

15 The upward movement of the valve 25 is limited by downwardly extending projections 34 formed on the upper wall of the chamber 13.

The valve 25 reciprocates in the chamber 20 13, and when in use, the conduits 12 are connected to drain pipes. The conduit 33 is designed to be connected to a steam pipe leading to the valve chamber of a cylinder.

When the valve is in operation, the steam 25 pressure from the valve chest of the engine acting on the upper face of the valve 25 will cause the said valve to be closed on its co-acting valve seat 28, so that the L-shaped ports 14 will be covered by the valve 25.

30 As soon as the pressure has been released, the springs 23 will move the valve 25 upwardly until the upper face of the valve engages with the projections 34 on the upper wall of the cylindrical chamber 13, and any 35 excess steam or water will then pass through the passageways 14 in the wall of the cylindrical chamber 13, and be delivered to the conduit 20, and so pass to waste. The conduits 12 which have been connected to drain 40 pipes will allow the water flowing from the said conduit to pass through the conduits 12, L-shaped ports 14 into the lower part of the cylindrical chamber 13, and thence through the conduit 20 to waste.

45 To allow the water to pass through the conduit 20 to waste, it should be noted that the stem 24 of the valve 25 is Y-shaped in

cross section, so that when the valve is displaced from its seat there is adequate clearance between the stem and conduit 20. 50

The action of this valve is automatic, and the valve will be closed as soon as the steam pressure is brought to bear on the same, and it will be opened under the action of the spring 23 after the steam pressure has been 55 removed.

As many changes could be made in the above construction, and many apparently widely different embodiments of my invention, within the scope of the claim, constructed without departing from the spirit or scope thereof, it is intended that all matter contained in the accompanying specification and drawings shall be interpreted as 60 illustrative, and not in a limiting sense. 65

What I claim as my invention is:—

A drain valve of the character described, comprising an upper and a lower portion having screw threaded engagement with each other, the lower portion fitting into a 70 suitable threaded recess in the upper portion, a conical valve seat formed integral with the lower portion, the upper portion having laterally extending conduits arranged in alignment, a cylindrical chamber in the upper portion communicating with the said conduits through L-shaped ports, part of the 75 said ports are formed in the side wall of the said chamber, while the completion of the lower arms of the L-shaped port is formed 80 in the lower portion of the casing, and extends into the conical valve seat between the top and bottom thereof, a valve on the conical valve seat having a sliding fit with the aforesaid chamber, the said chamber being 85 provided with suitable by-passes around the valve.

In witness whereof I have hereunto set my hand in the presence of two witnesses.

FREDERICK KNIGHT.
